CLOTHESLINE

Filed June 22, 1927

WITNESS: *John J. Moran*

Thomas J. James
INVENTOR
BY *Victor J. Evans*

ATTORNEY

UNITED STATES PATENT OFFICE.

THOMAS J. JAMES, OF BUCKNER, VIRGINIA, ASSIGNOR OF ONE-HALF TO EDWARD W. HIGGINS, OF CREWE, VIRGINIA.

CLOTHESLINE.

Application filed June 22, 1927. Serial No. 200,735.

This invention relates to a clothes line, the general object of the invention being to so form the line that clothes can be easily and quickly attached thereto without the 5 use of pins.

Another object of the invention is to make the line of a plurality of links which are connected together by eyes so that the line can be folded into a compact bundle when not 10 in use.

A still further object of the invention is to so form the line that the clothes can be attached thereto and detached therefrom by a simple sliding movement of the clothes 15 on the line.

This invention also consists in certain other features of construction and in the combination and arrangement of the several parts, to be hereinafter fully described, 20 illustrated in the accompanying drawings and specifically pointed out in the appended claim.

In describing my invention in detail, reference will be had to the accompanying 25 drawings wherein like characters denote like or corresponding parts throughout the several views, and in which:—

Figure 1 is a view showing the line in use.

Figure 2 is a view of the unlooped wire, with the looped wire shown in dotted lines.

Figure 3 is a view of the looped wire, with the unlooped wire shown in dotted lines.

Figure 4 is a detail view of the looped 35 portion of the link.

As shown in these views, the line A is composed of a plurality of links B, each link being formed of two wires 1 and 2. The wire 1 has its terminals bent back upon it- 40 self to form the eyes 3 and the ends of the other wire 2 are twisted around the eye forming portions of the other wire 1, as shown at 4, to hold such portions in place. The central portion of the wire 2 is bent to 45 form a circular loop 5, the terminals of which extend in opposite directions and with one terminal on one side of the other wire 1 and the other terminal on the opposite side of said wire 1 so that said other wire 1 lies 50 between the terminals. The wires are twisted together in a long twist, as shown at 6.

With this invention, the clothes are placed on the line with the parts to be attached to 55 the line to the left of the loops. Then the

clothes are slid along the line to the right and as the portions to be attached to the line reach the loops, they will pass between the terminals of the loops and the unlooped wires of the links and thus be caused to pass 60 between the two wires of each link so that they will be gripped and held by the two wires. The right hand corner of the clothes can be pulled to a point adjacent the end of the link as the portion of the clothes gripped by the wires will readily pass between the twisted portions of the wires. Thus it will be seen that the clothes can be easily and quickly placed on the line as it is simply necessary to place corners or other small 65 portions of the clothes on the line and then slide the clothes along the line to cause such portions to enter the loops which directs them between the wires. For instance, the corner portions can be looped around the line 70 adjacent the loops 5, and then by sliding the clothes along the line, the corners will enter the loops 5 and will automatically pass between the two wires, as the first terminal of the loop 5 will cause the corner of the 75 clothes to enter the loop and then the second terminal will direct the corner between the wire forming the loop and the second wire which passes between the terminals of the loop and then upon a further move- 80 ment of the clothes, the corners will engage the twisted portions of the two wires and thus be firmly held between the two wires. After the clothes are placed on one side of the line, other clothes can be placed on the 85 opposite side, the clothes being moved to the right on each side of the line. When the clothes are to be detached from the line, they are moved toward the left so that they will free themselves of the line as they pass 90 through the loops.

When the line is to be stored, the links can be folded together so that the line will occupy but little space. With this line, the clothes can not only be easily and quickly 95 attached thereto and detached therefrom, but the clothes are firmly held on the line without the use of pins and there is no danger of the clothes being torn by the line.

It is thought from the foregoing description that the advantages and novel features of my invention will be readily apparent.

I desire it to be understood that I may make changes in the construction and in the combination and arrangement of the sev- 110

eral parts, provided that such changes fall within the scope of the appended claim.

What I claim is:—

5 A clothes line comprising a plurality of links having interengaging eyes at their ends, each link being formed of a pair of wires, one of said wires having a circular loop intermediate its ends, the ends of the

looped part overlapping and the straight portions extending in opposite directions ¹⁰ from the looped part, with the second wire passing between the overlapping ends of the loops, the portions of the wires on each side of the loop being twisted together.

In testimony whereof I affix my signature.

THOMAS J. JAMES.
